DESIGN FOR A MAGAZINE RACK

Edward A. Herrera, Huntington, N. Y.

Application August 1, 1944, Serial No. 114,677

Term of patent 7 years

(Cl. D33—2)

To all whom it may concern:

Be it known that I, Edward Anthony Herrera, a citizen of the United States, residing at 635 Park Avenue, in the county of Huntington and State of New York, have invented a new, original, and ornamental Design for Magazine Rack, of which the following is a specification, reference being had to the accompanying drawing, forming part thereof.

Fig. 1 is a side elevational view of a magazine rack showing my new design;

Fig. 2 is an end view thereof; and

Fig. 3 is a top plan view.

I claim:

The ornamental design for a magazine rack, as shown.

EDWARD A. HERRERA.
